WALL CONSTRUCTION

Merton T. Straight, Des Moines, Iowa

Application February 21, 1944, Serial No. 523,326

5 Claims. (Cl. 72—127)

1

This invention relates to a wall construction and in particular to a wall construction of the type comprised of horizontal rows of blocks, arranged in tiers and secured together by mortar.

It is an object of this invention to provide an improved wall construction.

Another object of this invention is to improve the thermal insulating properties of a brick wall construction.

A further object of this invention is to provide in a brick wall construction, means adapted to economize on the amount of mortar used in the wall and to increase the thermal insulating properties of the wall, without impairing the strength of the wall.

Yet another object of this invention is to provide in a brick wall construction means preventing moisture passing through the mortar from one side of the wall to the other.

A still further object of this invention is to provide in a wall construction comprised of an inner wall and an outer wall, means for preventing the inner and outer walls being in a thermal exchange relation.

A feature of this invention is found in the provision of a block wall construction having a space therein, extended longitudinally of the wall between the sides thereof, adapted to receive in wedged engagement an elongated flexible tube, resistant to water. Mortar for holding the blocks together is confined by the tube to each side of such space, so that the tube prevents moisture passing through the mortar from one side of the wall construction to the other.

Another feature of this invention is found in the provision, in a wall construction comprised of an inner wall and an outer wall spaced apart from each other, of elongated flexible tubes wedged in the space between the walls and arranged longitudinally of the walls. The tubes divide the wall space into a plurality of separate dead air passages so as to prevent a circulation of air, by convection, across the adjacent sides of the inner and outer walls whereby to improve the thermal insulating characteristics of the wall construction.

Further objects, features and advantages of this invention will be apparent from the following description when taken in connection with the accompanying drawing in which:

Fig. 1 is a plan perspective view of one form of wall construction of this invention comprising an inner wall and an outer wall;

Fig. 2 is a perspective view of an elongated flex-

2

ible tubular insert used in the wall construction of Fig. 1;

Fig. 3 is a transverse sectional view of the wall construction in Fig. 1;

Fig. 4 is illustrated similarly to Fig. 3 and shows a modified form of the tubular insert; and

Fig. 5 is a transverse sectional view of a modified form of wall construction of this invention.

Referring to the drawing there is illustrated in

Fig. 1 a wall construction comprised of an inner or main wall 10 formed of horizontal rows of tiles or blocks 11 arranged in tiers having mortar, indicated at 15, for holding the blocks together in a usual manner. An outer or veneer wall 12 laterally spaced from the inner wall 10 is formed of bricks 14 also arranged in horizontal rows tiered one above the other and secured together by mortar 15. The inner wall 10 and outer wall 12 are connected together by hooks 14 extended between the walls and anchored at its ends in the mortar between adjacent rows of blocks 11 and bricks 14 in the walls 10 and 12, respectively. As thus far described the wall construction is of a type well known in the prior art.

In walls of this construction the outer surfaces of the blocks 11 and bricks 14 are usually glazed, or the blocks and bricks are composed of a hard material so as to be substantially impervious to water. The mortar 15, however, is of a rather loose consistency so that even after it becomes hardened moisture is able to pass therethrough by capillary action. Where the space 16 between the walls 10 and 12 is relatively small the mortar 15, which overruns each wall, extends into the space 16 so that mortar from the walls is in contacting engagement, or at least in an overhanging relation within the space 16. As a result moisture from the mortar in the outer wall 12 is able to pass to the mortar in the inner wall 10 and drains outwardly from the side 17 of the inner wall. This passage of moisture through the wall is, of course, objectionable because of the resulting dampness in the space 16 adjacent the side 17 of the inner wall 10 and the possibility of resultant injury to material located in such space.

A further objection to this prior art wall construction is found in the fact that the wall readily conducts heat from one side to the other so as to be a relatively inefficient thermal insulator. Thermal conduction through the wall occurs by virtue of an air circulation being set up within the space 16 by convection. Thus assuming the outer wall 12 to be cold and the inner

wall 10 warm, air in the space 16 will flow downwardly across the wall 12 and upwardly across the inner wall 10. By virtue of this circulation of air the wall 10 is constantly cooled and continuously draws heat by conduction from the side 17, and, therefore, is always continuously cooled to in turn cool the space adjacent thereto.

These objections in the above described wall construction are overcome in the present invention by the insertion within the space 16 of flexible elongated tubular members or inserts 18 (Figs. 1 and 2). Each insert or tube 18 has water repellent characteristics and may be composed of tar paper, of heavy paper or thin metal with an asphalt coating, or of thin rust-proof metal. The tubes 18 are horizontally positioned in a vertically stacked relation within the space 16 so as to extend longitudinally of the walls 10 and 12, with this assembly of the tubes 18 being made during the building up of the wall construction.

The diameter of the tubes 18 relative to the width of the space 16 is such that the tubes are slightly flattened as indicated at 19, and wedged in the space 16 between the walls 10 and 12. By virtue of this assembly of the tubes 18 in the wall construction the space 16 is divided into a plurality of separated passages or pockets extended longitudinally of the walls 10 and 12. The air within the space 16 is thus incapable of being circulated by convection since it is confined in pockets formed by the tubes. The walls 10 and 12, therefore, are thermally insulated from each other to in turn provide for a wall construction having efficient thermal insulating properties.

As illustrated in Figs. 1 and 2 two adjacent rows of bricks 14 provide a vertical height of the outer wall 12 which is the equivalent of a single row of blocks 11 in the inner wall 10. The size of each tube 18 is such that when it is inserted in a wedged position within the space 16 its vertical height is substantially equal to the vertical height of a row of bricks 14, with the flattened tube portions 19, resulting from the tube being wedged within the space 16, extending substantially to the top of a row of bricks 14. As is clearly illustrated in Fig. 1 this construction and arrangement of the tubes 18 provides for alternate tubes in the space 16 having their flattened portions 19 extended substantially to the top of a row of blocks 11. Thus when mortar is placed on the top of a row of bricks 14 or blocks 11 the mortar is prevented from entering the space 16 by the tubes 18 so that no mortar overruns the walls 10 and 12 into the space 16.

Since the mortar which flows or overruns into the space 16 performs no useful function in strengthening the wall construction, such mortar is entirely wasted. Thus the holding of the mortar within the confines of a wall 10 and 12 by the tubes 18 produces a saving in the mortar without in any way decreasing the overall strength of the wall construction. It has been found in practice that this saving in mortar substantially covers the cost of the tubes 18. With the mortar in each wall 10 and 12 thus separated by the tubes 18 a defined gap or space is provided between opposite horizontal layers of mortar 15 in the walls 10 and 12 so as to positively eliminate any passage of water through the mortar from one wall to the other.

In Fig. 4 the wall construction of Fig. 1 is shown constructed with tubes 18a which are

somewhat smaller in diameter than the tubes 18 so that the tubes 18a are relatively spaced vertically within the space 16. Each tube 18a is positioned opposite the top of a row of bricks 14 in the outer wall 12, with every other tube 18a being opposite the top of a row of blocks 11 in the inner wall 10. The function of the tubes 18a is similar in all respects to the tubes 18 described in connection with Figs. 1 and 3 so that a further description of the tubes 18a is believed to be unnecessary.

The modified form of wall construction in Fig. 5 is comprised of horizontal rows of blocks 21, with each block being of the usual type having a longitudinally extended groove 22 in the top and a longitudinally extended groove 23 in the bottom thereof. In building this wall construction the lower groove 23 in one tier is positioned opposite an upper groove 22 in a next vertically adjacent block 21 so that the grooves 22 and 23 define a space 24 which extends longitudinally within the wall. In the normal construction of the wall in Fig. 5 the space 24 is entirely filled with mortar 15 so that moisture is able to pass by capillary action from one side to the other of the wall. To prevent this passage of moisture through the wall a tube 18 is located in the space 24 in a wedged position so as to be in contacting engagement with the sides of the grooves 22 and 23. During the assembly of the wall the tube 18 is initially positioned in the upper grooves 22 of lower blocks 21 and mortar 15 placed on such lower blocks adjacent the tube 18. A next adjacent upper row of blocks 21 is then placed 30 on the lower blocks with their bottom grooves 23 opposite the upper grooves 21 of the lower row of blocks. The tube 18 thus prevents any mortar 15 from passing into the space 24 and provides a gap between the portions of mortar 15 to each 35 side of the space 24 so as to prevent any flow of moisture through the mortar 15 from one side of the wall to the other.

Although the invention has been described with respect to several preferred embodiments thereof it is not to be so limited since changes therein can be made which are within the full intended scope of this invention as defined by the appended claims.

I claim:

1. A wall construction comprising an inner wall and an outer wall spaced apart from each other, with each wall comprised of a row of horizontal blocks arranged in tiers and secured together by mortar, and flexible water repellent tubes wedged in the space between said inner wall and outer wall and extended longitudinally of said two walls, said tubes retaining the mortar at said space within the confines of a corresponding wall to obstruct the passage of moisture from the outer wall to said inner wall through the mortar.
2. A wall construction comprising an inner wall and an outer wall having a space therebetween, with each wall being comprised of blocks arranged in horizontal tiers and having mortar therebetween, and flexible water repellent cylindrical members of a diameter such that they can be wedged in the space between said two walls, said members being positioned horizontally between said two walls, with a member having a wedging surface adjacent the top level of a tier of blocks to retain the mortar between adjacent tiers in a wall within the confines of the wall.
3. In a wall construction comprising horizontal tiers of blocks and mortar between said tiers for securing the blocks together, means for prevent-

5

ing moisture from travelling by capillary action through said mortar from one side of the wall construction to the other side thereof including a water repellent flexible tube, said blocks being constructed and arranged to form a space within the wall extended longitudinally of the wall, said tube being horizontally positioned in said space and wedged between the sides of the space, with the mortar between adjacent tiers of blocks being confined by a tube from passing into said space.

4. In a wall construction comprising horizontally tiered blocks with each block being of a type having a groove in the top and bottom extended longitudinally of the block, with a top groove in a block in one tier forming a space with the bottom groove in a block in a next adjacent tier, with said two blocks being secured together by mortar therebetween, means for preventing mois-

6

ture from travelling through said mortar laterally of the wall including a flexible tube having water resistant characteristics, with the tube being positioned in said space longitudinally of the blocks and of a size adapted to be wedged between the sides of corresponding grooves in adjacent tiers of blocks to hold the mortar against entering said space.

5. A wall construction comprised of horizontal tiers of blocks with a layer of mortar between adjacent tiers, and having a longitudinal passage therein extended across a plane common to said layer of mortar, and a flexible water repellent tube in said passage intercepting said plane to provide an air pocket within the wall and to keep any moisture in said layer of mortar from seeping across said passage.
